UNITED STATES PATENT OFFICE

JOHN A. MAHNK, OF BEAUMONT, CALIFORNIA

DESIGN FOR AN IDENTIFICATION TAG HOLDER

Application filed October 26, 1932. Serial No. 45,585. Term of patent 7 years.

To all whom it may concern:

Be it known that I, JOHN A. MAHNK, a citizen of the United States, residing at Beaumont, in the county of Riverside and State of California, have invented a new, original, and ornamental Design for an Identification Tag Holder, of which the following is a specification, reference being had to the accompanying drawing forming part thereof.

Fig 1 is a perspective view of an identification tag holder showing my new design.

Fig. 2 is a top plan view of the same, and Fig. 3 is an end elevation.

I claim:

The ornamental design for an identification tag holder as shown.

JOHN A. MAHNK.
